CLAIM

I claim the ornamental design for a front bumper assembly for a model vehicle, as shown and described.

DESCRIPTION

FIG. 1 is a top, right, front perspective view of a front bumper assembly for a model vehicle;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, right, rear perspective view; and,

FIG. 9 is a top, left, front perspective environmental view. In the drawings, the broken line showing of features of the front bumper assembly for a model vehicle illustrate portions of the front bumper assembly for a model vehicle that form no part of the claimed design; whereas, the broken line showing of the environmental view depicts environmental subject matter and is provided for the purposes of illustrating environmental structure and context.
